UNITED STATES PATENT OFFICE.

JOHN A. SMITH, OF JOHNSTOWN, PENNSYLVANIA, ASSIGNOR OF TWO-THIRDS
TO JAMES HART AND ABRAHAM WILKINSON, OF SAME PLACE.

BALANCED PISTON-VALVE.

SPECIFICATION forming part of Letters Patent No. 560,550, dated May 19, 1896.

Application filed June 28, 1895. Serial No. 554,359. (No model.)

To all whom it may concern:

Be it known that I, JOHN A. SMITH, a citizen of the United States, residing at Johnstown, in the county of Cambria and State of Pennsylvania, have invented a new and useful Balanced Piston-Valve, of which the following is a specification.

My invention relates to valves, and particularly to balanced piston-valves, the object in view being to provide a simple and efficient form of valve in which the valve members are adapted to be closed by the pressure of the fluid, the pressure being communicated to the outlet-valve member in either position of the inlet-valve member.

Further objects and advantages of this invention will appear in the following description, and the novel features thereof will be particularly pointed out in the appended claims.

In the drawings, Figure 1 is a section of a valve constructed in accordance with my invention, both valve members being shown seated. Fig. 2 is a similar view showing the inlet-valve open or unseated. Fig. 3 is a horizontal section on the plane indicated by the line 3 3 of Fig. 1. Fig. 4 is a detail view of the cap forming one of the equalizing-chambers detached.

Similar numerals of reference indicate corresponding parts in all the figures of the drawings.

Formed in the valve-casing 1 are the parallel bores or cylinders 2 and 3, with which communicate, respectively, the inlet and outlet ports 4 and 5. The cylinder-port 6 is arranged in the wall or partition between said bores or cylinders and communicates with the latter by means of ports 7 and 8, respectively.

Arranged in each bore or cylinder is a valve-seat 9, the seat in the inlet bore or cylinder 2 being arranged between the planes of the inlet-port 4 and communicating-port 7, and the seat in the outlet bore or cylinder 3 being located between the communicating-port 8 and the outlet-port 5. In the construction illustrated said valve-seats are threaded in the bores or cylinders; but it is obvious that they may be secured in place in any other suitable manner to provide for their removal

when it is necessary that they should be replaced or repaired.

The inlet and outlet valve members 11 and 12 are carried by the stems 13 and 14, which are arranged axially in the bores or cylinders, 55 compressible packing 15 being secured in contact with the face of each valve member by means of a compressing disk or nut 16. The bores or cylinders are preferably enlarged, as shown at 17, contiguous to each valve-seat to 60 provide space for the operation of the valve member, and the portions of the valve members remote from their faces are reduced, as shown at 18, to operate in the reduced portions 19 of the bores or cylinders, said reduced 65 portions being fitted with caps 20, which form equalizing-chambers 21. These reduced portions 18 of the valve members fit in the equalizing-chambers and are provided with packing-rings 22 of compressible material, held in 70 place by means of disks 23 and nuts 24.

The equalizing-chambers are in communication with each other through the connecting-channel 25, which is formed in the partition or wall interposed between the bores or 75 cylinders, the cylindrical inclosed portions of the caps 20 having openings 26, which communicate with said channel at its extremities.

The stem of the inlet-valve member 11 is provided with an axial bore or channel 27, 80 extending from a point below the valve member to the upper extremity, and therefore communicating at its opposite ends with the main portion of the bore or cylinder and the equalizing-chamber, and therefore the pressure of the fluid contained in the main portion of the bore or cylinder is communicated through the axial channel of the stem to the equalizing-chamber above the inlet-valve member to balance the pressure upon opposite sides of the valve member, and this pressure in the equalizing-chamber of the inlet-valve member is communicated through the connecting-channel 25 to the equalizing-chamber of the outlet-valve member, whereby pressure is exerted upon the rear side or the piston extension of the outlet-valve. Hence when there is pressure in the body portion of the outlet-valve-member bore or cylinder, caused by pressure in the cylinder 95 100

with which the port 6 communicates, the pressure upon opposite sides of both inlet and outlet valve members is equalized.

Secured to the stems of the valve members 5 and operating in the bores or cylinders upon the opposite sides of the valve member from said equalizing-chambers are plungers 28, also provided with packing-rings 29, and therefore, inasmuch as these plungers are exposed at 10 all times to the pressure in the body portions of the bores or cylinders, the pressure of the fluid will tend to close or seat the valve members if they are unseated or hold them seated if they are in their normal positions. In other 15 words, the plungers, by reason of the constant pressure thereon, operate to close and hold the valve members seated, whereby when it is necessary to unseat a valve to supply fluid to the cylinder or exhaust therefrom it is necessary to produce the necessary motion of the 20 valve member by mechanical means, such as an operating-lever 30, which I have shown fulcrumed at 31 and provided with bearing-points 32 and 33 to engage the exposed extremities of the valve-stems. It is unnecessary to connect the operating-lever with the valve-stems, for the reason that as soon as the valve members are released by the removal of positive pressure against their stems 25 30 said valve members will be closed by the pressure of the fluid. By the construction above described both valves cannot be open simultaneously, for the reason that pressure must be removed from one valve-stem before it 35 can be applied to the other, and as soon as the pressure is removed the valve member is seated by fluid-pressure.

It will be understood that the improved valve may be applied to use in connection 40 with steam, hydraulic, pneumatic, and other cylinders, or mechanisms employing fluid-pressure of different classes, and that various changes in the form, proportion, and the minor details of construction may be resorted to 45 without departing from the spirit or sacrificing any of the advantages of this invention.

Having described my invention, what I claim is—

1. A valve having a casing provided with 50 inlet and outlet cylinders respectively having inlet and outlet ports and communicating

with a cylinder-port, valve-seats arranged between the planes of the ports communicating with the cylinders, equalizing-chambers permanently exposed to cylinder-pressure, 55 and valve members arranged in the cylinders and having their rear sides exposed in the equalizing-chambers, whereby the valves when released are seated by the said pressure in the equalizing-chambers, substantially as 60 specified.

2. A valve having inlet and outlet cylinders provided, respectively, with inlet and outlet ports and communicating with a cylinder-port, seats arranged in the cylinders between the planes of the ports communicating therewith, valve members arranged in the cylinders and having piston extensions operating in equalizing-chambers which are respectively in communication with the cylinders 70 and exposed to cylinder-pressure, the stem of the valve member operating in the inlet-cylinder being bored to form a channel connecting the body portion of the cylinder with the communicating equalizing-chamber, and 75 plungers carried respectively by the stems of the valve members and exposed to a constant pressure of fluid in the body portions of the cylinders, substantially as specified.

3. A valve having inlet and outlet cylinders provided respectively with inlet and outlet ports and communicating with a cylinder-port, caps removably fitted in the extremities of the cylinders to form equalizing-chambers exposed to cylinder-pressure, valve members 80 arranged respectively in the cylinders and having piston extensions fitted in the equalizing-chambers, means for communicating pressure from the inlet-port to the equalizing-chamber at the end of the inlet-cylinder, 85 and plungers connected to the stems of the valve members and exposed to a constant pressure of fluid in the cylinders, substantially as specified.

In testimony that I claim the foregoing as 90 my own I have hereto affixed my signature in the presence of two witnesses.

JOHN A. SMITH.
